CLAIM

The ornamental design for a jewelry ring head, as shown and described.

DESCRIPTION

FIG. 1 is a perspective view of a jewelry ring head showing my new design;

FIG. 2 is a top plan view thereof;

FIG. 3 is a bottom plan view thereof;

FIG. 4 is a front elevational view thereof, the rear elevational view being a mirror image thereof;

FIG. 5 is a left side elevational view thereof, the right side elevational view being a mirror image thereof;

FIG. 6 is a perspective view of a second embodiment of a jewelry ring head showing my new design;

FIG. 7 is a top plan view of FIG. 6;

FIG. 8 is a bottom plan view of FIG. 6;

FIG. 9 is a front elevational view of FIG. 6, the rear elevational view being a mirror image; and,

FIG. 10 is a left side elevational view of FIG. 6, the right side elevational view being a mirror image thereof.

The broken lines shown on the drawings represent unclaimed portions of the design and form no part thereof.
